UNITED STATES PATENT OFFICE

ISAAC HANSEN, OF NEW ROCHELLE, NEW YORK

SAFETY CATCH

Application filed February 12, 1929. Serial No. 339,321.

This invention relates to lifts, and more particularly to an automatic safety catch for preventing a lift from falling upon failure of the supporting mechanism.

5 The invention applies particularly to lifts which are supported by a single cable secured to the top portion thereof, as for example, dumbwaiters, and provides means for locking the lift if the cable becomes slack either due to breakage or due to interruption of the 10 downward movement of the lift, such as by increased friction of the guiding mechanism which might cause the lift to stick temporarily. If the descent of the lift is interrupted 15 while the cable is being fed downwardly the cable will become loose and when the lift is subsequently released will allow the same to drop until the cable again becomes tight. The force of this drop has at times been sufficient 20 to damage the mechanism, or in the case of wooden dumbwaiters, to sever the connections between the cable and the top thereof.

In accordance with the present invention 25 whenever the cable becomes loose the safety catch is automatically applied and prevents further descent until the supporting cable is again tightened. This prevents the lift from dropping and in fact prevents all further 30 movement until it is again raised by reversing the movement of the supporting table.

The invention comprises a gripping member which is normally carried on the lift in an inoperative position, but which is released 35 and is brought into engagement with the guideway of the lift whenever the supporting cable becomes loose. The grip is normally held out of engagement with the guideways by a resilient member and is accordingly prevented 40 from causing wear of the guideways except when it is brought into operation as a safety catch.

The invention also consists in certain new and original features of construction and 45 combinations of parts hereinafter set forth and claimed.

Although the novel features which are believed to be characteristics of this invention will be particularly pointed out in the claims 50 appended hereto, the invention itself, as to

its objects and advantages, the mode of its operation and the manner of its organization may be better understood by referring to the following description taken in connection with the accompanying drawings forming a 55 part thereof, in which

Fig. 1 is a plan view of a lift showing a pair of safety catches applied thereto;

Fig. 2 is an enlarged detail view of the safety catch and the supporting cable; 60

Fig. 3 is a section taken on the line 3—3 of Fig. 2 showing the catch in disengaged position;

Figs. 4 and 5 are detail views of modifications of the gripping member; 65

Fig. 6 is an enlarged detail view of the control lever and support therefor; and

Fig. 7 is a detail of the clamp.

Like reference characters denote like parts in the several figures of the drawings. 70

In the following description and in the claims parts will be identified by specific names for convenience, but they are intended to be as generic in their application to similar parts as the art will permit. 75

Referring to the drawings more in detail, the invention is shown as applied to a lift 10 which may comprise a dumbwaiter or other analogous device. The lift is provided with fingers 11 which engage with the guideways 12. A supporting cable 14 is firmly secured to the top of the lift in any desired manner 80 and serves to control the vertical position thereof.

The safety catch as shown more in detail 85 in Fig. 2 comprises a housing 15 which may be cast or formed in any other desired manner and is provided with a flange 16 which may be secured to the side 17 of the lift by any suitable means as by bolts 18. The housing is also provided with a pair of outwardly extending ears 20 through which suitable bolts 21 may be passed for attaching the same 90 to the top portion of the lift 10.

Housing 15 is drilled to receive a rock shaft 95 such as a bolt 24 which is provided with a head 25 and a shoulder 26 for the purpose to be described. A second shoulder 27 is formed on the opposite end of said bolt, and threads 28 are provided for receiving a nut 100

29 and a lock washer 30, by means of which the bolt is secured in position in said housing.

The grip member 31 is provided with a recess which is inserted over shoulder 26 whereby said member is mounted for rotational movement with bolt 24. Lever 32 is also provided with a recess which is inserted over shoulder 27 of said bolt. The grip member 10 and lever are preferably formed slightly thinner than their cooperating shoulders in order to prevent the same from binding when the bolt is tightly secured in housing 15.

Lever 32 is provided with a hole 33 in which one end of a spring 34 is secured. The other end of said spring is permanently secured to the top of the lift as by pin 35. The end of lever 32 is provided with a hole 36 in which a flexible cable, such as wire 37, is secured. Said wire is passed through eyes 40, 41 (Fig. 1) which are secured in the top of lift 10 and is thence passed upwardly (Fig. 2) and secured to cable 14 by any suitable means such as clamp 42.

25 A type of clamp which may be employed is shown in detail in Fig. 7 as comprising a bolt 60, which may be inserted through cable 14 in any convenient manner, such as by spreading the fibers of the cable with a suitable tool and then threading the bolt between the separated fibers.

Clamps 61 and 62 are carried upon bolt 60 and are suitably curved to conform in general to the shape of cable 14. Clamp 63 is carried on bolt 60 adjacent clamp 61 and is curved in conformity with the outer surface of clamp 61. Grooves 64 and 65 are formed in clamps 63 and 61 respectively for receiving wire 37.

40 The entire assembly is secured by nut 66 and lock washer 67. It is obvious that pressure applied to said nut will cause clamp members 63, 61 and 62 to firmly engage cable 14 and wire 37.

45 Grip member 31 is preferably formed with a plurality of seizing elements such as short point 45 and a long point 46. The short point is adapted to engage the side of guide 12 when the member is rotated in response to the tension of spring 34. If the weight of the lift is such that point 45 is sufficiently strong to secure the same, point 46 will operate merely as an abutment but will not enter the guide member. If, however, the mechanism tends to drop after point 45 becomes engaged, further rotation of the grip will take place thereby bringing point 46 into engagement with the guide 12 for effectively checking the descent of the lift. The amount 55 of rotation of grip 31 is limited by suitable shoulders 47 (Fig. 6) which are formed on housing 15 and engage with lever 32 when said lever is in its extreme position.

In the modification shown in Fig. 4, grip 49 is provided with a plurality of points 50

which are positioned at different distances from the center of rotation of said grip. With this construction the upper point 50 will first be brought into contact with the guide member and the remainder of the points will be successively brought into contact therewith as the grip is further rotated due to slippage of the lift. It is to be noted that the gripping force is accordingly increased as required by an amount depending upon the 75 tendency of the lift to slide.

A second modification of the grip is shown in Fig. 5 which comprises a grip 52 formed with a single point 53 which is adapted to be brought into engagement with guideway 12 80 in the manner above pointed out.

In order to prevent the slides from being distorted due to the action of the gripping members on one side thereof it may be desired to provide a pair of such members as shown in Fig. 1 which operate in opposite directions whereby the lateral stress on the supporting mechanism is equalized.

The above described catch member is so positioned on the lift that spring 34 will normally tend to hold the grip in engagement with the guideway. The spring should be adjusted to provide the necessary force for bringing this grip into engagement and for causing the points thereof to enter the material of the guideway as above mentioned. Flexible cable or wire 37 which is secured to lever 32 is passed under eyes 40 and 41 and is then extended upwardly and secured to cable 14 in such manner that lever 32 is moved 100 against the tension of spring 34 a sufficient amount to disengage the grip from the operating guideway. When for any reason cable 14 becomes loose, the tension of wire 37 decreases, thereby permitting spring 34 to bring the grip into operating position.

It is to be noted that side strain on cable 14 is eliminated by positioning eye 41 comparatively close to the point of attachment of cable 14 whereby the wire and cable are caused to extend in the same general direction. The device above described is particularly applicable to wooden lifts, such as dumbwaiters which are commonly secured between wooden guideways. It is obvious, however, 115 that the device may be applied to other types of lifts provided the parts are made accordingly stronger. Furthermore the grip may contact with any stationary member. It is shown as contacting with the guideways for 120 purposes of illustration only.

While certain novel features of the invention have been shown and described and are pointed out in the annexed claims, it will be understood that various omissions, substitutions and changes in the forms and details of the device illustrated and in its operation 125 may be made by those skilled in the art without departing from the spirit of the invention.

What is claimed is:

1. In combination with a lift having a supporting cable, guideways in which said lift is adapted to slide, a safety catch member comprising a grip member, resilient means for holding said grip member in engagement with said guideways, a lever associated with said grip member and a flexible member interconnecting said lever and said supporting cable, said member being threaded through members secured in the top of said lift, one of said members being located near the point of attachment of said supporting cable.

2. A safety catch for a lift comprising a housing, a bolt extending therethrough, said bolt having a head and a shoulder adjacent said head, a grip member carried on said shoulder, a second shoulder and a lever carried thereon, means associated with said lever for holding said grip member in operative position and additional means associated with said lever for moving said grip member to an inoperative position.

3. A clamping device for securing a flexible member to a stranded cable comprising a bolt adapted to be passed through said cable, curved clamps carried by said bolt and adapted to engage said cable, a third clamp adjacent one of said curved clamps and having means for engaging said flexible member, and means for clamping said elements together for securely gripping said cable and flexible elements.

In testimony whereof I have hereunto set
35 my hand.

ISAK HANSEN.
